US00D770173S

(12) **United States Design Patent** (10) **Patent No.:** **US D770,173 S**
Brophy et al. (45) **Date of Patent:** **** Nov. 1, 2016**

(54) **BAG**

(71) Applicant: **Smith & Nephew, Inc.**, Memphis, TN (US)

(72) Inventors: **Edward Brophy**, Argyll and Bute (GB); **David Chadwick**, Skipton (GB); **Kathryn Ann Leigh**, Saint Petersburg, FL (US)

(73) Assignee: **Smith & Nephew, Inc.**, Memphis, TN (US)

(**) Term: **14 Years**

(21) Appl. No.: **29/492,729**

(22) Filed: **Jun. 2, 2014**

(51) LOC (10) Cl. **03-01**

(52) U.S. Cl.

USPC **D3/232**

(58) **Field of Classification Search**

(57) **CLAIM**

The ornamental design for a bag, as shown and described.

DESCRIPTION

FIG. 1 is a top, front and left side perspective view of a bag; FIG. 2 is a top, rear, and right side perspective view thereof.

FIG. 3 is a front view thereof.

FIG. 4 is a rear view thereof.

FIG. 5 is a left side view thereof.

FIG. 6 is a right side view thereof.

FIG. 7 is a top plan view thereof.

FIG. 8 is a bottom plan view thereof.

FIG. 9 is a top, front, and left side perspective view thereof, with the exterior flaps shown in the open position for ease of illustration.

FIG. 10 is a top, rear, and right side perspective view thereof, with the exterior flaps shown in the open position for ease of illustration.

FIG. 11 is a front view thereof, with the exterior flaps shown in the open position for ease of illustration.

FIG. 12 is a rear view thereof, with the exterior flaps shown in the open position for ease of illustration.

FIG. 13 is a left side view thereof, with the exterior flaps shown in the open position for ease of illustration.

FIG. 14 is a right side view thereof, with the exterior flaps shown in the open position for ease of illustration.

FIG. 15 is a top plan view thereof, with the exterior flaps shown in the open position for ease of illustration; and,

FIG. 16 is a bottom plan view thereof, with the exterior flaps shown in the open position for ease of illustration.

1 Claim, 14 Drawing Sheets
